UNITED STATES PATENT OFFICE

CHARLES L. MOON, OF DETROIT, MICHIGAN, ASSIGNOR TO MECHANICAL HANDLING SYSTEMS, INC., OF DETROIT, MICHIGAN, A CORPORATION OF MICHIGAN

CONVEYER

Application filed February 6, 1928. Serial No. 252,381.

The invention relates to conveyers and more particularly to that type of conveyer having a linear member, such as a chain, extending over rotatable members, such as sprockets. One of the objects of the invention is to provide a transfer device for actuating from the conveyer an object located beyond the axis of either rotatable member. Other objects of the invention reside in the 10 novel features of construction and combinations and arrangements of parts as more fully hereinafter set forth.

In the drawings:—

Figure 1 is a side elevation, partly broken away, of a portion of a conveyer system embodying my invention;

Figures 2, 3 and 4 are cross sections, respectively, on the lines 2—2, 3—3 and 4—4 of Figure 1;

Figure 5 is a plan view of the transfer device;

Figure 6 is a view similar to Figure 1, showing a modification;

Figure 7 is a cross section on the line 7—7 25 of Figure 6.

In the present instance, I have embodied my invention in a conveyer system which is used in the manufacture of pottery and particularly in the baking of pottery, where the 30 kilns are provided with longitudinally extending troughs containing sand and the cars for carrying the saggers are provided with side plates depending below their bases, but with their lower edges engageable in the 35 sand for sealing the mechanism contained in the lower parts of the kilns from the heat in the upper parts. The cars are moved sidewise at both the loading and unloading ends of the kilns and because of the depending 40 sand sealing plates upon the cars, the conveyers for moving the cars to or from the kilns must terminate short of the ends of the sand sealing plates.

In detail, a kiln (not shown) having the 45 above described sand sealing troughs is provided with a longitudinally extending track 1. 2 is the car for carrying the saggers, this car having the sand sealing plates (not shown) depending from the sides of the base 50 3 and the flanges 4 depending from the ends

of the base and preferably integral therewith. A transfer track 5 extends transversely of the track 1 and is located beyond the loading end thereof and in a lower plane. A transfer truck 6 having the wheels 7 for 55 engaging the track 5 carries the transverse track 8. These tracks are each formed with parallel rails and the tracks 1 and 8 are adapted for engagement with the wheels 9 of the car 2. The arrangement is such that a 60 sagger carrying car 2 may be loaded with a sagger which contains pottery to be baked and then moved sidewise upon the transfer car 6 to bring the track 8 upon this transfer car into alignment with the track 1 in the 65 kiln, after which the sagger carrying car may be released for removal from the transfer car to the kiln.

For the purpose of transferring the sagger carrying car from the track 8 to the track 1, 70 I have provided a transfer device which is operated by the conveyer and does not interfere with the sidewise movement of the sagger carrying car, but is movable between the sand sealing plates of this car to engage a 75 flange depending from its base. The conveyer comprises the linear member 10 running over the rotatable members 10'. The linear member is a chain having alternate links formed of the single bars 11 and the 80 spaced bars 12. The rotatable members are sprockets, one of which is driven by suitable means such as an electric motor (not shown). The upper portion of the conveyer chain is supported upon the upwardly opening channel-shaped track 13, which latter is carried by the uprights 14 of the conveyer frame. 15 is the transfer device having the carriage 16 and the dog 17. This carriage is located above the upper portion of the conveyer 85 chain 10 and has the longitudinally extending side flanges 18, which slidably engage the track 19 formed of the angle bars 20, the latter being supported upon the uprights 14 of the conveyer frame and having horizontal 90 flanges extending over the side flanges of the channel-shaped track 13. The carriage is pivotally connected at one end preferably to the attachment 21, which extends downwardly between the horizontal flanges of the angle 95 100 bars 20.

bars 20 and is rigidly secured to the inner sides of the bars 12 of a conveyer chain link as by means of the bolts and nuts 22. The dog 17 is pivotally connected by the pin 17' to the integral upwardly extending furcations 23 at the opposite end of the carriage.

The transfer device being designed to pull the sagger carrying car from one track to another track, the dog is pivotally connected to the carriage in such a way that when the transfer device is being advanced to place the dog under the sagger carrying car the dog will swing in a clockwise direction upon engagement of its upwardly extending arm with the end flange of the car to allow its upwardly extending arm to pass under the flange, the swinging being limited by the upwardly extending arm coming into contact with the furcations. However, as soon as the upwardly extending arm has passed the flange, the dog will again swing back to normal position, by reason of the horizontally extending arm of the dog being of greater weight than the upwardly extending arm. Upon movement of the transfer device in the opposite direction the upwardly extending arm engages the rear side of this flange and is held from disengagement by reason of the horizontally extending arm engaging the carriage. The track 19 extends beyond the track 13 and the axis of the sprocket 10' to terminate short of the ends of the sand sealing plates upon the sagger carrying car. Also the length of the carriage 15 between its points of connection to the conveyer chain and the dog is such that the upwardly extending arm of the dog may engage the end flange of the sagger carrying car beyond the track 19. The carriage further has the depending projections 16' for engaging the inner edges of the horizontally extending flanges of the angle bars 20 to guide the carriage and hold the same from lateral disengagement from the track formed by these angle bars.

For the purpose of automatically limiting movement of the conveyer in opposite directions, I provide a limit switch trip 24, which comprises the bars 24' rigidly secured to the top of the carriage 16 and the cam-shaped trips 24'', which are adjustably secured to the under sides of the bars. One of these trips is engageable with the roller at the outer end of the arm 25 of the limit switch 26, which latter is secured to the conveyer frame and, as shown in the present instance, one of the angle bars 20. There are two of these switches located upon the conveyer frame and engageable by the same trip for controlling the movement of the conveyer in opposite directions.

In the modification shown in Figures 5, 6 and 7, the transfer device is designed to move the sagger carrying car 27 from the track 28 to the transfer track 29 upon the transfer car 30, the conveyer being located between the

ends of the track 28. In this instance all the parts, with the exception of the transfer device have the same arrangement as those previously described. The transfer device differs in that the dog 31 is pivotally mounted upon the carriage to swing in the opposite direction (a counterclockwise direction) from that of the dog 17, the upwardly extending arm of the dog 31 being engageable with the outer side of the end flange of the sagger carrying car to push the car and the horizontally extending arm of this dog being engageable with the carriage to hold the upwardly extending arm in engagement with the outer side of the flange.

What I claim as my invention is:

1. In a conveyer apparatus, the combination with a conveyer movable between definite limits, of a transfer device actuated by said conveyer for actuating an object beyond said conveyer, and automatically operable means for controlling the operation of the conveyer.

2. In a conveyer apparatus, the combination with a rotatable member and a linear member extending over said rotatable member, of a transfer device actuated by said linear member for actuating an object beyond the axis of said rotatable member, and means operable by the transfer device for controlling the operation of the linear member.

3. In a conveyer apparatus, the combination with a sprocket and a chain extending around said sprocket, of a transfer device actuated by said chain for actuating an object beyond the axis of said sprocket, a limit switch for controlling the operation of the sprocket and means carried by the transfer device for actuating said switch.

4. In a conveyer apparatus, the combination with a rotatable member and a linear member extending around said rotatable member, of a transfer device including a carriage connected to said linear member, a dog upon said carriage, said carriage being adapted to extend beyond the axis of said rotatable member and said dog being engageable with an object beyond the axis of said rotatable member for actuating the object, and means automatically operable upon a predetermined movement of the carriage in one direction to stop the rotation of said rotatable member.

5. In a conveyer apparatus, the combination with a conveyer frame, a sprocket, a chain extending around said sprocket and a track supported upon said frame for the upper portion of said chain, of a transfer device including a carriage connected at one end of said chain, and a dog pivotally mounted upon the opposite end of said carriage, and a track upon said frame extending beyond the axis of said sprocket for supporting said carriage when the latter extends beyond the axis of said sprocket.

6. In a conveyer apparatus, the combination with a frame, a rotatable drive sprocket

upon said frame, a chain extending around said sprocket and a limit switch upon said frame for controlling the driving of said sprocket, of a transfer device including a carriage connected to said chain and adapted to extend beyond the axis of said sprocket, work engaging means upon said carriage, and a trip mounted upon said carriage for actuating said limit switch.

5 7. In a conveyer apparatus, the combination with a conveyer movable in opposite directions, of a transfer device actuated by the conveyer for actuating an object beyond said conveyer and means operable by the transfer device for automatically limiting movement of the conveyer in opposite directions.

10 8. In a conveyer apparatus, the combination with a conveyer frame, a sprocket, a chain extending around said sprocket and a track supported upon the frame for supporting the upper portion of said chain, of a second track carried by the frame above the track aforesaid, a transfer device including a carriage mounted upon the second track and connected at one end to said chain and a dog pivotally mounted upon the opposite end of said carriage, and a member upon said frame extending beyond the axis of the sprocket for supporting the carriage when the latter extends beyond the

20 25 30 axis of the said sprocket.

In testimony whereof I affix my signature.
CHARLES L. MOON.
